BABY CARRIAGE AND THE LIKE

Georg Henry Sixten Holmström, Goteborg,
SwedenApplication July 25, 1945, Serial No. 607,002
In Sweden April 24, 1943

12 Claims. (Cl. 296—27)

1

My invention relates to baby carriages and the like which are provided with a body of stiff material as sheet metal, wood, fibre, basket work and such like.

The principal object of my invention is the provision of a baby carriage with a body of stiff material which can be folded together so that it in this state needs very little space and is easy to transport.

Another object of the invention is a foldable baby carriage which can be folded and unfolded in one simple operation only.

A further object of the invention is a foldable baby carriage, the parts of which will automatically lock each other in proper state at the end of the unfolding operation.

Other objects and advantages of the invention relating to the particular arrangement and construction of the various parts will become apparent as the description proceeds.

In the accompanying drawing:

Fig. 1 is a longitudinal section view of the baby carriage in its extended state.

Fig. 2 is an end view of the same with its parts folded together.

Fig. 3 is an enlarged fragmentary longitudinal section view of the one end portion of the baby carriage including modified sectional side walls.

Fig. 4 is a cross section of the arrangement shown in Fig. 3.

Fig. 5 is an enlarged fragmentary longitudinal section view of the portion shown in Fig. 3 but in another embodiment.

Referring in detail to the different parts of the baby carriage 2 designates a bottom for the carriage with its padding 2', which bottom is fixed to a bottom frame 1. A back 3 for the body is swingably connected to the foremost end of the bottom frame 1 by means of pivots 12. The bottom frame is supported by support arms 4 turnably connected to the bottom frame 1 as well as to a base frame 5 of the carriage, the base frame being carried on the carriage axles by intermediate springs. When the bottom is pushed rearwards the support arms will swing downwards and the bottom will be lowered. To hold the bottom in raised position the back 3 is provided with catches 6 which in upright position of the back and of side walls 7 of the body will grip over cross directed side pins 13 in the side walls as shown in Fig. 1 and Fig. 3. When the back 3 is swung rearwards the catches will be disconnected and the bottom is free to be lowered.

In the embodiment of Figs. 1 to 4 the side walls 7 of the body are mounted to the base frame 5

2

by means of hinges 8 or such like, so that they can be folded inwardly, and the arrangement is such that the bottom frame 1 in its normal raised position will prevent the side walls 7 to be folded towards each other as shown in Fig. 4.

The side walls 7 are held in their normal upright position also therethrough that their lower portions situated beneath the hinge pivots will be hindered in the swinging movement by the raised normal push handle bow 9, which lower portions at the folding movement will swing outwardly and upwardly. The push handle bow is swingably mounted to the base frame 5 and can from a horizontal position be swung upwardly and take up two alternative positions as shown in Fig. 1 by 9 and 9'. In this position the handle cooperates with catches 10, 10' on the outer sides of the side walls and will at the same time press against side guides 11 on the side walls helping to make the locking of the side walls secure and rigid.

When the body of the baby carriage is to be folded together the push handle 9 is swung down to horizontal position. Thereafter the back 3 is swung down releasing the catches 6 from the side pins 13. When now the back is drawn rearwards the bottom will follow and be lowered by a downward swinging movement of the support arms 4, and the side walls 7 will clap down over the back overlapping each other as seen in Fig. 2. As the bottom in its normal position locks the side walls in upright position, the folding of the side walls is in dependence of the lowering of the bottom. The arrangement of the different parts is such that the movements of the same can be to a certain degree carried through simultaneously. The unfolding of the body occurs in reverse order, and at the end of the unfolding operation the parts will be automatically locked together.

In the embodiment of Fig. 5 the side walls are foldably mounted on the bottom frame 1 instead of on the base frame 5 with the result that the side walls will follow the lowering movement of the bottom. In upright position the side walls are held by the push handle and are themselves locking the bottom in its normal position by means of locking pins 15 extending from the side walls beside the support arms 7 as seen in Fig. 5. Thus the lowering of the bottom is in this case in dependence of the folding of the side walls as the side walls must be folded previous to the lowering of the bottom.

The side walls 7 can be divided along the horizontal hinge axle line 14 as shown in Figs. 3 and

4, so that the upper portions only of the side walls will take part in the folding operation the lower portion 7' being fixed relative to the frame 5. The back can be arranged to hold the side walls in upright position. The carriage can be provided with two backs or gables and with one or more axles. If desired the back can be arranged to be swung down on the already folded side walls.

Although preferred embodiments of my invention have been illustrated it will be understood that modifications may be made within the spirit and scope of the appended claims.

I claim:

1. A baby carriage comprising a base frame, support arms swingably connected thereto, a body of stiff material including side walls and a bottom which is carried by the swingable support arms, the bottom being lowerable from its normal position by a downwardly swinging movement of the support arms, the side walls being foldably mounted, and locking means to lock the side walls in upright position and the bottom in normal position.

2. A baby carriage comprising a base frame, support arms swingably connected thereto, a body of stiff material including side walls and a bottom which is carried by the swingable support arms, the bottom being lowerable from its normal position by a downwardly swinging movement of the support arms, the side walls being foldably mounted, the folding of the side walls being in dependence of the lowering of the bottom, and locking means to lock the side walls in upright position and the bottom in normal position.

3. A baby carriage comprising a base frame, support arms swingably connected thereto, a body of stiff material including side walls and a bottom which is carried by the swingable support arms, the bottom being lowerable from its normal position by a downwardly swinging movement of the support arms, the side walls being foldably mounted, the folding of the side walls being in dependence of the lowering of the bottom, locking means to lock the side walls in upright position and the bottom in normal position, and the locking means for the side walls consisting of the bottom in its normal position.

4. A baby carriage comprising a base frame, support arms swingably connected thereto, a body of stiff material including side walls and a bottom which is carried by the swingable support arms, the bottom being lowerable from its normal position by a downwardly swinging movement of the support arms, the side walls being foldably mounted, the folding of the side walls being in dependence of the lowering of the bottom, locking means to lock the side walls in upright position and the bottom in normal position, the locking means for the side walls consisting of the bottom in normal position, and the locking means for the bottom comprising coupling parts of the side walls cooperating with coupling parts of the bottom.

5. A baby carriage comprising a base frame, support arms swingably connected thereto, a body of stiff material including side walls and a bottom which is carried by the swingable support arms and a back swingably connected to the bottom, the bottom being lowerable from its normal position by a downwardly swinging movement of the support arms, the side walls being foldably mounted relative to the bottom, the folding of the side walls being in dependence of the lowering of the bottom, locking means to lock the side

walls in upright position and the bottom in normal position, the locking means for the side walls consisting of the bottom in normal position, the locking means for the bottom comprising coupling parts of the side walls cooperating with coupling parts of the bottom, said coupling parts consisting of catches on the back of the body and side pins in the side walls over which the catches are engageable in the upright position of the back.

6. A baby carriage comprising a base frame, support arms swingably connected thereto, a body of stiff material including side walls and a bottom which is carried by the swingable support arms and a back swingably connected to the bottom, the bottom being lowerable from its normal position by a downwardly swinging movement of the support arms, the side walls being foldably mounted relative to the bottom, the folding of the side walls being in dependence of the lowering of the bottom, locking means to lock the side walls in upright position and the bottom in normal position, the locking means for the side walls consisting of the bottom in normal position as well as of a swingably mounted push handle bow and holders on the side walls cooperating with the handle bow, the locking means for the bottom comprising coupling parts of the side walls cooperating with coupling parts of the bottom, said coupling parts consisting of catches on the back of the body, side pins in the side walls over which the catches are engageable in the upright position of the back.

7. A baby carriage comprising a base frame, support arms swingably connected thereto, a body of stiff material including side walls and a bottom which is carried by the swingable support arms, the bottom being lowerable from its normal position by a downwardly swinging movement of the support arms, the side walls being foldably mounted, the side walls being attached to the bottom to be lowered therewith, and locking means to lock the side walls in upright position and the bottom in normal position.

8. A baby carriage comprising a base frame, support arms swingably connected thereto, a body of stiff material including side walls and a bottom which is carried by the swingable support arms, the bottom being lowerable from its normal position by a downwardly swinging movement of the support arms, the side walls being foldably mounted, the side walls being attached to the bottom to be lowered therewith, the lowering of the bottom being in dependence of the folding of the side walls, and locking means to lock the side walls in upright position and the bottom in normal position.

9. A baby carriage comprising a base frame, support arms swingably connected thereto, a body of stiff material including side walls and a bottom which is carried by the swingable support arms, the bottom being lowerable from its normal position by a downwardly swinging movement of the support arms, the side walls being foldably mounted, the side walls being attached to the bottom to be lowered therewith, the lowering of the bottom being in dependence of the folding of the side walls, locking means to lock the side walls in upright position and the bottom in normal position, and the locking means for the bottom consisting of coupling parts of the side walls cooperating with parts of the bottom.

10. A baby carriage comprising a base frame, support arms swingably connected thereto, a body of stiff material including side walls and a bottom

which is carried by the swingable support arms, the bottom being lowerable from its normal position by a downwardly swinging movement of the support arms, the side walls being foldably mounted, the side walls being attached to the bottom to be lowered therewith, the lowering of the bottom being in dependence of the folding of the side walls, locking means to lock the side walls in upright position and the bottom in normal position, the locking means for the bottom consisting of coupling parts of the side walls co-operating with parts of the bottom, the locking means for the side walls consisting of the swingable mounted normal push handle bow and holders on the side walls cooperating with the handle bow.

11. A baby carriage comprising a base frame, support arms swingably connected thereto, a body of stiff material including side walls and a bottom which is carried by the swingable support arms, the bottom being lowerable from its normal position by a downwardly swinging movement of the support arms, the side walls being foldably mounted, locking means to lock the side walls in upright position and the bottom in normal position, and side walls overlapping each other in their folded position.

12. A baby carriage comprising a base frame, support arms swingably connected thereto, a body of stiff material including side walls and a bottom which is carried by the swingable support arms, the bottom being lowerable from its normal position by a downwardly swinging movement of the support arms, the side walls being foldably mounted, locking means to lock the side walls in upright position and the bottom in normal position, the side walls being divided, so that the upper portion only of them is foldably mounted, and the side walls overlapping each other in their folded position.
